STOKER APPARATUS, INCLUDING A UNI-
FORMLY INCREASING PITCH FEED
SCREWArthur O. Dady, Flossmoor, Ill., assignor to Sears,
Roebuck and Co., Chicago, Ill., a corporation of
New York

Application July 12, 1944, Serial No. 544,497

5 Claims. (Cl. 110—45)

1

This invention relates to stokers and is concerned more particularly with the feeding of coal or other granular material which is beset with characteristic impediments such as packing or coking effects.

It is an object of my invention to provide a feed screw which will deplete the hopper substantially uniformly throughout the length of the hopper.

Another object is to provide a coal feeding mechanism by means of which the coal is accurately metered to the burner.

An additional object is to provide a coal feeding mechanism requiring substantially less work to feed a given quantity of coal per hour than is true of conventional coal feeding devices particularly when low fire conditions in a stoker retort produce back draft burning and coking in the feed screw terminal flights.

Another object is to provide a coal feed screw having terminal flights of increased wall thickness whereby to better resist wear under severe abrasive conditions while yet maintaining equal or slightly increased volumetric characteristics as regards space intervening the screw flights.

It is also an object of my invention to provide a novel method of forming a coal feed screw.

Further objects and advantages of the invention will appear as the description proceeds.

The invention will be better understood upon reference to the following description and the accompanying drawings, in which:

Fig. 1 is a longitudinal view of a tube and screw in assembly with a coal hopper, feed tube and burner or retort in accordance with one form of my invention.

Fig. 2 is an enlarged sectional view taken as indicated by the line 2—2 in Fig. 1.

Figs. 3 and 4 are views similar to Fig. 1 showing additional modifications of feed screws.

Fig. 5 shows a part of an apparatus for forming a ribbon or other elongated strip, rod or bar into a conveyor worm flight.

Figs. 6 to 9 show various flight cross-sectional shapes.

Referring now more particularly to the drawings, there is shown at 20 a gear case from which projects the usual square or other polygonal end of the coal feed screw drive shaft 22 received in a correspondingly formed socket 24 formed on the core 25 of a feed screw 26. The portion 28 of the flight 30 disposed within the entering sleeve 32 of the coal hopper 34 is preferably of substantially uniform diameter with relatively small clearance from the sleeve to prevent escape

2

of coal from the hopper in the direction of the gear case 20.

The diameter of the flight 30 at the wall 36 of the hopper 34 is relatively small, as shown at 38, and gradually increases in diameter, without change in pitch, substantially to a point not less than approximately one pitch or turn before reaching the opposite wall 40 of the hopper, i. e., substantially throughout that portion of the screw which serves as the coal collecting section.

This construction is considerably advantageous over the conventional collecting section, which is of substantially uniform diameter. With the conventional collecting section, the only portion thereof which collects coal from the hopper is the portion nearest the drive end which is in contact with the coal, and thus it will be seen that the hopper gradually empties from the drive end toward the burner end, and accordingly increasing portions of the feeding section of the flight become progressively idle. It has been found in practice that under these circumstances the smaller size coal in the hopper segregates or settles to the bottom, and thus the burner 25 does not receive the desired mixture of coal. Since the flow rate of combustion air is determined by the proportions of the mixture of large and small coal fed to the burner, and inasmuch as this mixture affects the fuel bed resistance to the flow of air, it will be apparent that under such circumstances the air flow rate will not be optimum at all times.

With a collecting section having a gradually increasing flight diameter, the draining of coal by said section from the hopper is made substantially uniform because the subsequent screw flights have greater intervening space capacity and hence take on additional coal as the diameter increases. With this construction, it has been found of additional advantage that the smaller size coal does not segregate in the hopper, but rather that the coal is delivered in the desired mixture to the burner, and thus the combustion air flow is substantially optimum at all times.

45 Welded as at 42 to the wall 40 of the hopper 34 is a metering and crushing block housing 44 with which is associated a block 46 held in assembly therewith by a cam 48 pivoted on a bail 50 whose ends (not shown) engage under flanges (not shown) extending laterally from the housing 44. Welded as at 52 to the housing 44 or formed integrally therewith is a recessed flange 54 for the reception of one end 58 of a coal feed tube 60. Welded as at 62 to the adjacent portion of 55 the coal feed tube 60 is a flange 64. Bolts 66

applied to the flanges 54 and 64 hold the housing 44 and coal feed tube 60 in tight abutment. The other end 68 of the coal feed tube 60 is suitably coupled to the neck 70 of a burner or retort 72.

The screw 26, from a point approximately at 74, preferably within the hopper and adjacent the inner wall 40 thereof, to a point approximately at 76, preferably slightly beyond the metering and crushing block assembly, is of uniform pitch and uniform diameter, said diameter being only slightly smaller than the interior diameter of said assembly, the fit being such as substantially to preclude leakage of any coal between the flight and said assembly, and to prevent the passage of gas or fumes back into the hopper. This portion of the screw serves as the metering section, insuring the delivery of a precise quantity of coal to the burner or retort.

From approximately the point 76 to the free end 78 of the screw, the screw is of uniformly increasing pitch. The delivering section extends from the metering section to approximately the point 80, at the burner end of the delivery tube 60, and, throughout the metering and delivery sections, the flight is of uniform diameter. The interior diameter of the coal feed tube 60 preferably exceeds that of the metering and crushing assembly, providing a slight clearance 82 between the tube and the flight. The purpose of the increased pitch of the delivering section over that of the metering section is to allow the level of the coal issuing from the crusher block assembly to drop as indicated by the dash-dot line 84 and thus materially cut down the resistance between the coal and the tube as the coal is moved toward the burner by the screw. In this connection it is to be observed that the delivering section of the screw, due to its greater pitch, has a capacity for delivering a greater quantity of coal than is supplied to it from the metering region. Since obviously the delivering section cannot deliver more coal than is supplied to it, the corresponding portion of the feed tube 60 will run partly full, with resulting slippage of a portion of the coal between the tube and the edges of the flight, thereby reducing crushing and preventing packing. This is essential or at least desirable particularly in a long screw such as is used in a bin feed stoker where frictional resistance is proportionately greater.

Adjacent the burner end 68 of the tube 60 the level of the coal rises substantially to the top of the tube, due to the resistance offered by the green coal within the burner. From approximately the point 80 to the free end 78 of the screw, the flight is of abruptly reduced diameter generally conforming to the curvature of the adjacent bottom portion of the burner 72. From the drive end to approximately the point 88 the flight may be of substantially uniform thickness. From approximately the point 88 to the free end 78, the flight 30 is of increased thickness to provide increased surface for wear. Failure generally results from the wear of this portion of the screw before the remainder of the screw is seriously affected. Since the pitch of the screw flight is a gradually increasing one and since the wall thickness is correspondingly of increasing degree the portage volume between the flights may remain constant or at but slightly increasing capacity.

In accordance with the form of my invention shown in Fig. 3, the diameters of the various sections of the flight 92 of the screw 93 correspond with those of the flight 30 of Fig. 1. However, in

Fig. 3 the flight is of uniformly increasing pitch from the point 94, at the drive end of the hopper, to the burner end 96. With this construction the coal in the coal feed tube (not shown) levels off as indicated in dash-dot lines at 84 with resulting reduction in crushing and packing. The discharge end portion 100 of the flight of the screw 93 is gradually thickened like the corresponding end of the screw 26 of Fig. 1.

The flight 106 of the screw 107 in Fig. 4 is of uniform diameter throughout, except, of course, at its discharge or burner end 108, and is of uniformly increasing pitch from its drive end 109 to its burner end. The discharge position, i. e., approximately the last two turns of the flight 106, is thickened as in the screws shown in the other figures.

In the manufacture of coal feed screws, it is considerably less expensive to apply the flight as a ribbon and weld it to the core, than it is to form the screw by casting. Indeed it is impossible to cast screws such as those shown in Figs. 3 and 4 with patterns which screw out of the mold. I have devised an effective, efficient and inexpensive method of forming the flight from a ribbon, strip or other attenuated material. In accordance with the embodiment of the invention shown in Fig. 1, for example, I form a short flight section 28 from a strip on a suitable mandrel of the same diameter as the core 25 of the screw, the outside diameter of this flight section being uniform and slightly less than the inside diameter of the hopper sleeve 32, then slip the section 28 onto the core until the section bears substantially the relation to the core shown in the drawing, and then weld the section to the core. I then secure an end of the core, or a mandrel 112, to a chuck 114 carried by a shaft 115 driven as by a motor or belt drive 116 through suitable reduction gearing (not shown) so as to rotate the mandrel at a relatively low speed. Through suitable means such as gearing in a gear case 118, the shaft 115 may drive a lead screw 120 and, by using an appropriate gear ratio or other suitable means, the screw may be driven at the desired speed. The lead screw 120 is parallel to the mandrel 112 and substantially coextensive therewith. A tool post carriage 122 has a nut 124 about the lead screw 120 and is constrained to linear movement by suitable guides (not shown). The carriage may be provided with spaced vertical hardened steel guide rolls 126 arranged to engage the faces of a ribbon or other strip 128 and a spool-like rearwardly disposed guide member whose core or shaft portion 130 engages the upper edge 132 of the strip and whose flanges 134 engage the faces of the strip. If desired, an additional hardened steel roll may be provided for engagement with the inner (lower) edge of the strip 128, although such roll may be dispensed with since the strip will tend to be thrust upward as it is applied to the mandrel 112.

The chuck 114 has a drive pin, hook or other suitable strip-gripping or retaining means 140. When the carriage 122 is disposed adjacent said retaining means 140, the starting end 142 of the strip is extended to said means after passing beyond the spool and rolls. When the machine is in operation with the structure thus far described, the lead screw 120, rotating in the direction indicated by the arrow 144, will move the carriage 122 to the right at a uniform speed, the speed depending on the selection of the interchangeable gears in the gear case 118. This is the construction which could be employed if it were desired

to form a flight of uniform pitch throughout the length of the core.

However, where it is desired to form a flight of uniformly increasing pitch, either throughout the length of the core as shown in Figs. 3 and 4, or throughout a portion of the core as shown in Fig. 1, this could be done by mechanism operating to advance the lead screw 120 axially in the direction of feed of the carriage 122 simultaneously with the rotation of the lead screw, in such manner that the carriage would be caused to translate at a progressively increased speed. This result may be obtained in various ways. For example, I may provide a cam 150 mounted on a shaft 152 driven from the shaft 115 through suitable gear reduction mechanism 154, the cam acting on the lead screw 120 through a follower 156 journaled in the screw and abutting the screw at 157 to advance it at uniformly increasing speed. The cam may of course be varied in design to correspondingly move the lead screw. The follower is held against rotation by guide means 158. If it is desired to form a flight of which a portion is of uniform pitch and another portion of progressively varying pitch, as shown in Fig. 1, the cam would be designed with a portion of zero grade and a ramp of progressively or uniformly increasing grade. A spring 160 may be employed to constantly urge the lead screw and follower toward the cam.

The strip 128, being first formed with the desired variations in width and thickness corresponding to the desired design of flight, has imparted to it by the above mechanism an edgewise curvature substantially equal to the curvature of the core or mandrel 112. The free end 142 is pointed either before or after the formation of the coil, and the coil is then arranged in the desired position on the core and tack-welded or continuously welded thereto as shown at 162 in the various figures.

When the strip is bent around the core, the portion outside the neutral axis is stretched and thereby thinned, and the portion at the inside of the neutral axis is compressed and hence thickened. Thus if a strip of rectangular cross-section is used, the flight will become trapezoidal in cross-section, with the thicker portion encircling the core. A rectangular flight section may be obtained by using a trapezoidal strip of the proper dimensions with the thicker part at the edge which will be disposed outside during the coiling process. The brunt of the wear must be borne by the outside of the flight, it is therefore preferred that the outside be thicker to prolong the life of the flight. With a strip trapezoid of suitable dimensions, a flight could be formed with a resulting trapezoid which is thicker at the outside than at the inside, as shown at 170 in Fig. 6, or special shapes of flight with the outside portions thickened on the coal-conveying face, i. e., the face directed toward the burner, as shown by way of example only in Figs. 7, 8 and 9 at 172, 174 and 176, respectively, may be employed.

While there is shown and described herein certain specific structure embodying the invention, it will be manifest to those skilled in the art that various modifications and rearrangements of the parts may be made without departing from the scope of the invention, and that the same is not limited to the particular forms herein disclosed.

I claim:

1. A stoker mechanism for feeding coal to a heating unit comprising, a coal supply hopper,

a heating unit retort, a cylindrical conduit extending from the hopper to the retort and through which coal is delivered from said hopper to said retort, and a rotary screw conveyor 5 extending within said conduit comprising an axial core around which are secured spiral screw flights of which the pitch is uniformly increasing for a major portion of its length in said conduit at its retort end whereby packing of coal 10 within said conduit such as results from coking effects during low-fire conditions in said retort will be prevented from wedging or otherwise resisting the rotation of said conveyor.

2. A screw feed mechanism for coal burning heating systems comprising in combination, a coal supply bin provided with a discharge hopper, a retort having an under-feed opening on a horizontal level with said bin hopper, a cylindrical conduit connecting said retort with said bin and including an intermediate section functioning as a volume metering chamber, and a feed screw rotatable within said conduit comprising an axial shaft having at one end a rotary power coupling and having wound spirally about 25 it a screw flight having a progressively increasing pitch from said metering chamber to said retort whereby to counteract against packing effects of coal such as is induced by coking during low-fire burning conditions within said retort.

3. A screw feed mechanism for coal burning heating systems comprising, a coal supply bin equipped with a discharge hopper, a retort having an under-feed opening, a cylindrical conduit connecting said hopper with said retort including an intermediate section provided with a metering passageway, a feed screw extending to a point of marginal entry within said retort, and having close fitting engagement within said 40 metering section, said feed screw comprising an axial shaft around which is wound a spiral flight having a progressively increasing pitch at least from the metering section to said retort whereby, as coal is advanced towards said retort, a continuously increasing portage space is provided between the flights of said screw to prevent packing of coal as during low-fire burning conditions within said retort.

4. Stoker feed apparatus for coal burning systems comprising, in combination with a supply 50 hopper and a combustion retort, a conveyor including a cylindrical conduit extending between said supply hopper and said combustion retort and having a conduit metering section, and a screw confined in said conduit with a portion 55 underlying said supply hopper and a foremost end marginally extending into said retort, said conveyor screw comprising a screw metering section intermediate said supply hopper and said combustion retort having close fitting chambered reception in said conduit metering section, and said screw for a major portion of its length and extending to the retort having a flight having a progressively increasing pitch and a diameter substantially constant within said 60 metering section and continuing constant into said combustion retort whereby coal advanced to said retort is afforded continuously increasing space between the flights of said screw in order to offset packing effects such as result 65 from coking during back-draft conditions in said retort.

5. Stoker feed mechanism comprising, in combination with a supply hopper and a combustion retort, means for preventing coke packing during 70 low-fire burning conditions within said re-

retort including a conveyor comprised of a tubular conduit extending between said hopper and said retort, and a conveyor screw extending from within said hopper through said tubular conduit and having marginal entry into said retort, said screw having a plurality of helical flight portions, the conduit adjacent the hopper having relatively snug fit with the flight portions thereat to constitute a metering section, and the conduit between the metering section and 10 said retort having significant clearance with the flight portion of said screw thereat and constituting a delivery section, said screw being of uniformly increasing pitch in the direction of feeding and continuing to said retort whereby 15 to afford continuously increasing space accommodations to coal as it is advanced to said retort.
